ROCKING CHAIR

Earl E. Lockwood, 35 Crosby St.,
East Hartford, Conn. 06118

Filed Jan. 15, 1971, Ser. No. 106,941

Term of patent 14 years

Int. Cl. D6—02

U.S. Cl. D6—49

FIG. 1

FIG. 2

FIG. 3

FIG. 4

FIG. 5

FIG. 6

FIG. 1 is a perspective view of the rocking chair showing my new design.

FIG. 2 is a front view thereof.

FIG. 3 is a top view thereof.

FIG. 4 is a bottom view thereof.

FIG. 5 is a rear view thereof.

FIG. 6 is a right-hand side view of the rocking chair, the left-hand side view being a mirror image thereof.

I claim:

The ornamental design for a rocking chair, as shown and described.
